UNITED STATES PATENT OFFICE.

THEODORE P. BROWN, OF WORCESTER, MASSACHUSETTS, ASSIGNOR TO SIMPLEX PIANO PLAYER COMPANY, OF WORCESTER, MASSACHUSETTS, A CORPORATION OF MASSACHUSETTS.

AUTOMATIC PLAYING ATTACHMENT FOR MUSICAL INSTRUMENTS.

SPECIFICATION forming part of Letters Patent No. 772,208, dated October 11, 1904.

Application filed March 20, 1903. Serial No. 148,660. (No model.)

To all whom it may concern:

Be it known that I, THEODORE P. BROWN, a citizen of the United States, residing at Worcester, in the county of Worcester and State of Massachusetts, have invented a new and useful Automatic Playing Attachment for Musical Instruments, of which the following is a specification.

This invention relates to a pneumatically-controlled playing attachment of that class which are employed for striking the keys of a piano or for similar purposes.

The especial object of this invention is to provide instruments of this class with protecting-screens or air-straining attachments which are so located that they will not interfere with prompt response of the instrument and which will prevent particles of dust or other material from choking up or clogging the ventilating-holes.

To these ends this invention consists of the automatic playing attachment for musical instruments and of the combinations of parts therewith, as hereinafter described, and more particularly pointed out in the claims at the end of this specification.

In the accompanying drawings, Figure 1 is a sectional view of sufficient parts of an automatic playing attachment for musical instruments to illustrate the application of my invention thereto, and Fig. 2 is a detail view of a channel-board to which the cloth covering or screen is applied.

In operating an automatic playing attachment for musical instruments of the class to which this invention relates one of the sources of greatest difficulty arises from the stopping up of the ventilating-holes which exhaust the air from the primary pneumatics after being operated. In spite of the most careful inspection and tests which may be made upon instruments of this class before they are shipped from the factory it will sometimes happen that one or more of the ventilating-holes become stopped up before the instrument reaches the purchaser. This may be due to the fact that a small piece of sawdust or other light material may be left in one of

the tracker-board channels or other passages, and in the ordinary construction of such musical instruments such small particles of sawdust, dust, or other material are liable to be sucked up against the ventilating-disk and to stop up or obstruct one of the ventilating-holes, or in other cases it sometimes happens that small particles of dust or other foreign matter are drawn down through the tracker-board channels and choke up one or more of the ventilating-passages. I regard this as a most serious drawback in a musical instrument, because whenever a ventilating-hole becomes plugged up the corresponding note will fail to speak or will not respond as quickly as required to secure the best results.

The especial object of this invention is to overcome this difficulty by providing a dust-screen which will protect the ventilating-holes and prevent foreign matter from lodging therein, but which will be so located that it will not interfere with the tracker-board channels or other passages leading to the primary pneumatics—that is to say, in an automatic playing attachment for musical instruments constructed according to my invention the dust-screens are located in the channels which lead from the primary pneumatics to their ventilating-openings. In practice I have covered the face of the channel-board which carries the ventilating-disks with a facing of cheese-cloth or other material sufficiently open in mesh to permit air to be drawn therethrough, while fine enough to prevent the passage of particles of dust or other material which would be liable to obstruct the ventilating-holes.

Referring to the drawings for a detail description of an automatic playing attachment for musical instruments constructed according to my invention, 10 designates the tracker-board, which co-operates with a strip of perforated paper in the ordinary way. Extending down from the tracker-board 10 are pipes or tubes 11, which connect to channels leading to primary pneumatics 12. Operated by each of the primary pneumatics 12 is a valve 13 for admitting air to operate a valve-con-

trolling pneumatic 14, which pneumatic 14 controls a flapper-valve 15, which flapper-valve 15 controls the exhausting of air from one of the main or primary pneumatics 16. The movable section of each of the main pneumatics 16 has an arm which operates a rod or wire 17, having a striking-cushion at its lower end for operating the keys of a piano or similar instrument. These parts may be of any of the ordinary or preferred constructions, and while I have shown an instrument of one well-known type it is to be understood that my invention is also applicable to constructions in which the operative parts are arranged in different relations to each other.

When one of the primary pneumatics 12 has been operated to sound a note, the pneumatic must be restored to normal position. This is done by exhausting the air from the primary pneumatic through a channel extending through a channel-board 18 to a small ventilating - hole in a ventilating disk or washer 19—that is to say, in an automatic instrument of the class to which this invention relates whenever a note is sounded there will be more or less flow of air from the primary pneumatic in the direction of the arrow shown in Fig. 1. In order to prevent this current of air from carrying dust or other particles of matter liable to stop up the ventilating-hole in the disk 19, I provide the channel-board 18 with a covering of cheese-cloth or other comparatively open meshed material, as shown in Fig. 2. This covering 20 of cheese-cloth or similar material I have found in practice forms a very efficient screen for protecting the ventilating-holes, while at the same time this screen is so located that it does not in any way obstruct the tracker-board channels or interfere with the prompt response of the instrument.

I am aware that changes may be made in practicing my invention by those who are skilled in the art without departing from the scope thereof as expressed in the claims. I do not wish, therefore, to be limited to the construction I have herein shown and described; but

What I do claim, and desire to secure by Letters Patent of the United States, is—

1. In an instrument of the class described, the combination of a pneumatic, a channel leading from the pneumatic to the tracker-board, a channel leading from the pneumatic to a ventilating-hole, and a screen interposed between the pneumatic and ventilating-hole while the channel leading to the tracker-board is left unobstructed.

2. In an instrument of the class described, the combination of a series of pneumatics with passages extending therefrom, a channel-board connecting said passages to ventilating-openings, said channel-board having a single piece of cloth or other open-meshed material applied thereto to form a screen for protecting the entire series of ventilating-holes.

3. In an instrument of the class described, the combination of a series of primary pneumatics, a channel - board, ventilating - disks carried by the channel-board and having ventilating-holes for exhausting the air from the primary pneumatics, and a covering of cheese-cloth or similar open-meshed material secured on the face of the channel-board and forming screens for protecting the ventilating-holes.

In testimony whereof I have hereunto set my hand in the presence of two subscribing witnesses.
